US00D954667S

(12) **United States Design Patent** (10) **Patent No.:** **US D954,667 S**
(45) **Date of Patent:** **** Jun. 14, 2022**

(54) **POWER MODULE**

(71) Applicant: **Cree Fayetteville, Inc.**, Fayetteville, AR (US)

(72) Inventors: **Brice McPherson**, Fayetteville, AR (US); **Alexander Lostetter**, Fayetteville, AR (US)

(73) Assignee: **WOLFSPEED, INC.**, Durham, NC (US)

(**) Term: **15 Years**

(21) Appl. No.: **29/663,171**

(22) Filed: **Sep. 12, 2018**

Related U.S. Application Data

(63) Continuation-in-part of application No. 15/405,520, filed on Jan. 13, 2017, now Pat. No. 10,212,838.

(57) **CLAIM**

We claim the ornamental design for a power module, as shown and described.

DESCRIPTION

FIG. 1 is a right front side perspective view of the power module;

FIG. 2 is a top side view of the power module shown in FIG. 1;

FIG. 3 is a bottom side view of the power module shown in FIG. 1;

FIG. 4 is a right side view of the power module shown in FIG. 1;

FIG. 5 is a left side view of the power module shown in FIG. 1;

FIG. 6 is a front side view of the power module shown in FIG. 1; and,

FIG. 7 is a back side view of the power module shown in FIG. 1.

The subject matter shown in dashed lines, and any surface of the design not shown, including interior surfaces, form no part of the claimed invention.

1 Claim, 7 Drawing Sheets
